UNITED STATES PATENT OFFICE.

BENJAMIN F. CARGILL, OF CLEVELAND, OHIO, ASSIGNOR OF ONE-THIRD TO JAMES W. BROWN, ONE-THIRD TO RICHARD W. WINBUSH, AND ONE-THIRD TO MESHACH LIPFERD, ALL OF CLEVELAND, OHIO.

TROLLEY.

1,201,020

Specification of Letters Patent. Patented Oct. 10, 1916.

Application filed March 29, 1916. Serial No. 87,427.

To all whom it may concern:

Be it known that I, BENJAMIN F. CARGILL, a citizen of the United States, residing at Cleveland, in the county of Cuyahoga, and State of Ohio, have invented certain new and useful Improvements in Trolleys, of which the following is a specification.

This invention relates to trolleys and has for its object to provide a device of such class, with means in a manner as hereinafter set forth, for maintaining the trolley wheel in contact with the trolley wire during the travel of the wheel, more especially around curves.

15 Further objects of the invention are to provide a trolley which is unusually simple in its construction and arrangement, strong, durable, readily assembled, efficient in its use, and inexpensive.

20 With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

25 30 In the drawings wherein like reference characters denote corresponding parts throughout the several views:—Figure 1 is a sectional elevation of a trolley in accordance with this invention. Fig. 2 is a rear elevation.

35 Referring to the drawings in detail 1 denotes a trolley pole, having formed integral with its upper end a hollow semi-cylindrical member 2 which is offset at its bottom as at 3. Associating with the member 2 is a semi-cylindrical member 4 mounted upon the offset portion 3 and connected with the member 2 by detachable securing devices 5.

40 The inner face of the bottom of the member 1 and inner face of the lower portion of the member 4 are formed so as to provide a spherical socket 6 which opens into a cylindrical channel 7 formed by the inner faces of the members 2 and 4.

45 50 The reference character 8 denotes a harp having mounted in the arms thereof a shaft 9, which carries a trolley wheel 10. Formed integral with the base 11 of the harp 8 and depending therefrom is a stem 12 which has

one side thereof cut away as at 13. The lower end of the stem 12 terminates in a globular head 14 which is seated in the cylindrical socket 6. The stem 12 extends through the channel 7.

Arranged within the channel 7, is a coiled-spring 15, which opposes the cut away portion 13 and one end of the spring 15 is fixedly secured, as at 16, to the stem 12, and the other end of the spring 15 is fixedly secured as at 17, to the member 2. The function of the spring 15 is to tend to maintain the trolley wheel 10 in normal position, that is to say if the harp 8 is shifted at an angle, carrying the wheel 10 therewith, the said shifting movement will be against the action of the spring 15, and at the limit of such movement the spring 15 will restore the harp to normal position. When the harp is shifted the stem 12 will be carried there-

75 80 The head 14, in connection with the wall of the socket 6, provides what may be termed a ball and socket joint between the stem 12 and the pole 1.

What I claim is:—

1. A trolley comprising a pole having its upper end provided with a hollow semi-cylindrical member formed with a lateral offset at its joinder with the pole, a hollow semi-cylindrical member opposing the other member and seated on said offset, means for connecting said members together, said members forming a channel and having their lower ends provided with means to form a spherical socket, a harp carrying a trolley wheel and provided with a stem formed with a globular head, said stem mounted in said channel and said head seated in said socket, and a resilient connection between said stem and one of said members. 90 95

2. A trolley comprising a pole having its upper end provided with a hollow semi-cylindrical member formed with a lateral offset at its joinder with the pole, a hollow semi-cylindrical member opposing the other member and seated on said offset, means for connecting said members together, said members forming a channel and having their lower ends provided with means to form a spherical socket, a harp carrying a trolley wheel and provided with a stem formed with a globular head, said stem mounted in said channel and said head seated in said socket, 100 105

a longitudinally extending resilient connection between the stem and one of said means, and said stem having a longitudinal groove to provide a clearance for said resilient connection.

3. A trolley comprising a pole having its upper end provided with a hollow semi-cylindrical member formed with a lateral offset at its joinder with the pole, a hollow semi-cylindrical member opposing the other member and seated on said offset, means for connecting said members together, said members forming a channel and having their lower ends provided with means to form a spherical socket, a harp carrying a trolley wheel and provided with a stem formed with a globular head, said stem mounted in said channel and said head seated in said socket, and a resilient connection between said stem and one of said members, said stem integral with the base of the harp

and extending in the same axial line throughout.

4. A trolley comprising a pole having means on its upper end to form a channel terminating in a spherical socket, at the base of said means, a harp carrying a trolley wheel and having its base provided with a stem provided at its lower end with a globular head, said stem extending through said channel and said head seated in said socket, said stem having a longitudinal extending cut-away portion intermediate the ends thereof, and a resilient element seated in said cut-away portion and connected with the stem and with said means.

In testimony whereof I affix my signature in the presence of two witnesses.

BENJAMIN F. CARGILL.
